UNITED STATES PATENT OFFICE.

WILLIAM W. SWAYZE, OF WILMINGTON, DELAWARE.

PIN-LOCKING MEANS.

Application filed August 30, 1922. Serial No. 585,273.

One object of this invention is to provide relatively simple, effective and substantial means for retaining and locking a pin in a body or structure in which it is inserted, 5 and more particularly for immovably holding in place the pin connecting a hammer bar or arm with a hammer head or tip.

It is further desired to provide a novel retaining or locking device of the above type 10 which shall be of such construction as to permit of its ready assembly and also of its convenient disassembly when it is desirable to remove and renew the hammer tip or head.

15 These objects and other advantageous ends I attain as hereinafter set forth, reference being had to the accompanying drawings, in which,

Fig. 1 is a side elevation of a hammer bar 20 and head, showing my invention as applied thereto;

Fig. 2 is a horizontal section on the line 2—2, Fig. 1, and

Fig. 3 is an end elevation of the preferred 25 form of pin forming part of my invention.

In the drawings, 1 represents a hammer head or tip such as is customarily used in hammer crushers or pulverizers and this is cored to provide a recess 2 of substantially 30 rectangular section for the reception of an elongated hammer bar 3; there being two aligned and preferably circular holes in said head opening into said recess. At each end of the hammer bar is formed a circular hole 35 15, and a pin 4 is provided for coupling the bar to the head when said bar has been inserted in the recess 2. The pin 4 has an outwardly extending flange 5 at one end, and one face of the hammer head 1 is recessed 40 at 6 concentrically with the aligned holes for the pin to a depth preferably about double the thickness of said flange 5.

Projecting into this recess 6 from the wall 45 thereof are three or any other suitable number of radially extending lugs 8 placed in the present case 120° apart, and the flange of the pin is formed with three notches or recesses 7 to accommodate the lugs 8 and permit of its entrance into the recess 6 when 50 the pin is inserted in the aligned holes in the hammer head to couple this to a hammer bar extending into the cavity 2. The lugs 8 are so positioned that after the pin has been fully inserted in the hammer head, 55 it may be rotated without interference by the lugs with its flange and this latter is also

formed with a number of depressions 9 in its outer face the same angular distance apart as the notches 7 and lugs 8.

As a consequence of this construction, 60 when the pin is inserted to couple the hammer bar to the hammer head, its flange 5 may be so positioned as to permit the lugs 8 to pass through the recesses 7 and thus allow said flange to be seated on the bottom or inside face of the recess 6 under said lugs. By means of a suitable tool inserted in a passage or cavity 10 in the pin, the latter may now be turned through an angle of 60° for example, so that the depressions 9 65 are brought immediately under the lugs 8. The latter are now hammered down into said depressions with the result that the pin is held from rotation and at the same time is also effectually prevented from moving 70 longitudinally out of its given position in which it connects the hammer head and hammer bar.

Even though the hammer be subjected to the rough usage and wear incident upon the 75 work of a hammer crusher or pulverizer, it is a practical impossibility for the pin to become dislodged or to move into such position as to thereafter slide longitudinally out of its coupling position. If however by reason of wear of the hammer head, it is desirable 80 that it shall be removed and renewed, the lugs 8 may be forced out of the depressions 9 by the use of a suitable tool, after which the pin may be turned by a suitable member inserted in its squared or other than circular passage 10 until its notches 7 are aligned with the lugs 8. Thereafter 85 said pin may be forced longitudinally out of the hammer head, which may then be removed 90 from the hammer bar and replaced by a new head fixed in place as above described.

From the above description it will be seen 95 that my pin-retaining device is of the simplest construction, involving no elements other than the tongues 8 which are integral with the hammer head and the flange of the pin;—it being understood that the metal of the hammer is of such a nature as to permit 100 of the bending down and subsequent straightening of the lugs 8 without danger of their breakage.

I claim:

1. The combination of an element having 110 a hole therein, said hole having an enlarged portion with at least one bendable lug pro-

- 2
- jecting inwardly from the wall thereof, with a pin rotatably fitting into the hole, said pin having a flanged head recessed to allow the head to pass the lug when the pin is inserted in the hole, said head having an additional recess in its outer face to provide a seat into which the lug may be bent.
2. The combination of an element having a pin-hole therein with a pin in the hole, the pin having a notched flange formed to permit its insertion when occupying a predetermined position relatively to the element, the element being provided with a part capable of being bent into a depression in the pin to prevent the rotation and longitudinal movement of the pin.

3. The combination of an element provided with an opening therein and having an enlarged recess at one end of the opening and an integral lug extending into the recess 20 at a spaced distance from the bottom thereof, with a pin in said opening, said pin having a head located in the recess, the head having a notch in its periphery to permit the passage of the head past the lug and 25 having an additional recess in its head at one side of the peripheral recess, so that when the pin is partly turned the lug can be pressed into the additional recess in the head.

WILLIAM W. SWAYZE.
